M.L. Wickles & L.S. Olmsted.

Fare Box.

No 19,789.

Patented Mar. 30, 1858.

UNITED STATES PATENT OFFICE.

L. S. OLMSTED AND M. L. MICKLES, OF AURORA, ILLINOIS.

TICKET-HOLDER FOR RAILROAD-CARS.

Specification of Letters Patent No. 19,789, dated March 30, 1858.

To all whom it may concern:

Be it known that we, LEWIS S. OLMSTED and MYRON L. MICKLES, of Aurora, in the county of Kane and State of Illinois, have 5 invented a new and useful Improvement in Ticket-Holders for Railroad-Car Seats; and we do hereby declare the following to be a full, clear, and exact description of the construction and operation of the same, reference being had to the annexed drawings, making part of this specification, Figure 1 being a perspective view of the ticket-holder; Fig. 2, a similar view exhibiting the interior thereof, the doors being swung 10 open; Fig. 3, a similar view showing the upper door swung back and a portion of the operating parts not exhibited in the other figures.

Like letters designate corresponding parts 20 in all the figures.

The ticket-holder may be made of either cast or sheet metal, or of other suitable material, and containing two compartments, an upper and lower, as seen at (A and B). In 25 front of the upper chamber (A) is a door (C) upon which is a lock (D). When this door is opened a slot (E) is exposed in the upper part of the chamber (A). The flooring of this chamber (F) is made movable so 30 that it can slide forward and back by the action of the door (C). Attached to the lower corner of the door (C) is a projection (G) which acts upon one end of the lever (H). This lever is attached at its center 35 by the pin (I) and its extremity operates the sliding floor (F) of the upper chamber to which it is attached. The lower chamber (B) has a door in its front upon which is a lock, at L. The front plate of the upper 40 chamber has a glass plate (O) so placed that the contents of the chamber can be seen when the instrument is closed. Attached to the lower edge of the door (C) is a projection (P) extending along the lower edge of 45 the door, and so placed as to be in contact with the sliding floor (F). Upon closing the door this projection forces back the sliding floor, where it remains until the door is opened and it is forced back to its former 50 position.

The operation is as follows: On opening the door (C) the slot (E) is exposed, and the ticket of the passenger passed through it into the upper chamber and behind the glass plate (O) so that the printing on the ticket 55 can be read through the glass. The ticket will then rest upon the sliding floor of the upper chamber. Upon closing the door (C) the projection (P) upon the lower edge of the door forces back the sliding floor and the 60 ticket then rests upon the projection (P) and still in sight through the glass plate. The ticket remains in this position until the door (C) is opened, when it is dropped into the chamber below by withdrawing the projection (P). When the door (C) is drawn, say about half way open, the projection (G) upon the lower corner of the door acts 65 upon the lever (H) and thereby upon the sliding floor (F) throwing it forward to its 70 former position under the slot (E). The instrument is then ready to receive another ticket.

The ticket is thus held secure from both the passenger and conductor and can only 75 be taken by the person who has the key to the lower chamber, which should be the agent at the station.

What we claim as our invention and desire to secure by Letters Patent is— 80

A ticket-holder composed of two chambers, or compartments, A, B, into the upper one of which the ticket is placed and exhibited, and thence transferred to the lower one, in the act of closing and opening the 85 door of said upper compartment, by means of the movable floor F, and ledge, or projection P, all operating substantially in the manner and for the purposes herein specified.

LEWIS S. OLMSTED.
